UNITED STATES PATENT OFFICE.

ALBERT LEIGHTON, OF ERIE, PENNSYLVANIA.

COMBINED SUSPENDER-TAB AND BELT-LOOP FOR TROUSERS.

1,105,355.

Specification of Letters Patent. Patented July 28, 1914.

Application filed June 30, 1913. Serial No. 776,584.

To all whom it may concern:

Be it known that I, ALBERT LEIGHTON, a citizen of the United States, and a resident of Erie, in the county of Erie and State of Pennsylvania, have made a new and useful improvement in a Combined Suspender-Tab and Belt-Loop for Trouser, of which the following is a specification.

My present invention relates to suspender tabs, and more particularly to a suspender tab forming a permanent part of trousers, my object being to provide a flexible tab, the lower portion of which is secured to the inside of the waistband, and the upper portion of which is adapted to be turned down upon the outside of the waistband, this latter portion of the tab and the trousers being provided with coöperating fastening means whereby to secure the tab in turned down position and in such manner as to form a belt loop.

The means by which I accomplish the above are shown in the accompanying drawing, in which—

Figure 1 is a perspective elevation of the upper portion of trousers provided with my improvements. Fig. 2 is an elevation of one portion of the trouser's waistband showing one of the suspender tabs secured in turned down position to form a belt loop. Fig. 3 is a vertical sectional view taken substantially on line 3—3 of Fig. 2. Fig. 4 is a perspective elevation of the upper portion of trousers, illustrating a slightly modified form of my invention. Fig. 5 is an elevation of a portion of the trouser's waist band showing the modified form of my invention in turn-down position, as a belt loop, and Fig. 6 is a vertical sectional view taken substantially on line 6—6 of Fig. 5.

Referring now to Figs. 1 to 3 inclusive, I preferably provide suspender tabs indicated at A, A' and A², the lower ends of which tabs are connected or secured to the inner surface of the waistband of trousers indicated at B, by suitable means, such as for instance by buttons or preferably by riveting or stitching; as indicated at b in Fig. 1, the upper ends of these tabs carrying metallic loops a adapted to receive the usual flexible fasteners c of suspender straps C, or other device. Each of the tabs A, A' and A² is also provided adjacent its upper end with an outwardly opening socket fastener a', preferably located in the metallic loop as shown, and is formed of flexible material

whereby to permit the same to be turned down over the outer face of the trouser's waistband as particularly indicated in Fig. 2, the socket fastener a' coöperating with a stud fastener b' carried by the trousers. Thus with the fasteners a' and b' engaged as shown in Figs. 2 and 3, the main body portion of each of the suspender tabs extending over the outer surface of the trouser's waistband, forms, with the waistband of the trousers, a loop to receive the usual belt D. From this it will be seen that my invention is particularly effective for the purpose for which it is intended, and is highly useful, important, and convenient where the user, wearing suspenders, desires to remove his coat, at which time it is only necessary to detach the suspenders C by means of their flexible connections c, adjust the belt D in position and then turn down the tabs A, A', A² and secure the same over the belt as shown and described.

In the modified form of my invention as illustrated in Figs. 4 to 6 inclusive, the suspender straps D' are provided at their ends with slides or metallic loops d, and the flexible fasteners e are carried by the upper ends of the upwardly projecting trouser tabs E, the lower ends of which are permanently secured to the trousers in the same manner as previously described in connection with the tabs A, A' and A². In this manner the necessity for providing trouser tabs E with socket fasteners is done away with, inasmuch as the socket fasteners e' of the flexible members e may be utilized to coöperate with the studs F secured upon the outer surface of the trousers. This latter form of my invention will be cheaper, as may be readily seen.

My invention enables the manufacturer of trousers to dispense with the sewing on of buttons and saves time consumed and material used to make the ordinary belt loops, and in these instances will be a great saving to the manufacturer as well as economy and convenience to the user.

I claim:

1. The combination of trousers provided with fastening means at spaced points below its waist line, and flexible suspender tabs secured at their lower ends to the inside of the waistband at similarly spaced points of the trousers and adapted for connection at their upper ends to suspenders, said tabs being also provided at their upper ends with fas-

tening means to engage the said fastening means of the trousers when the tabs are turned down upon the outer face of the trousers, for the purpose described.

5 2. The combination with trousers, of suspender tabs secured to and extending upwardly from the waistband of the trousers and adapted to be turned down thereon, and means for fastening the tabs to suspenders when upstanding and to the trousers when turned down where y to form belt loops at spaced points around the waistband, for the purpose described.

10 3. The combination with trousers, of tabs suitably connected to the inside of the waistband and extending upwardly therefrom, attaching loops carried by the upper ends of the tabs for connection with suspenders when in upstanding position, and relatively 15 engageable means carried by the tabs and the outer surface of the trousers whereby to

secure the tabs in turned down position, for the purpose described.

4. The combination of trousers provided with fastening studs at spaced points below 25 its waist-line, flexible suspender tabs secured at their lower ends to the inside of the waistband at similarly spaced points of the trousers, and flexible connecting members at the upper ends of the tabs for engagement with 30 suspenders, said flexible connecting members having lower fastening studs and upper fastening sockets, the latter of which are also adapted for engagement with the trouser studs when the tabs are turned down upon 35 the outer face of the trousers, in order to form belt loops substantially as described.

ALBERT LEIGHTON.
